UNITED STATES PATENT OFFICE.

SAMUEL ROSS VASBINDER, OF FULTON, ILLINOIS.

DESIGN FOR A TIRE-CASING.

52,122.

Specification for Design. Patented June 18, 1918.

Application filed April 18, 1918. Serial No. 229,440. Term of patent 3½ years.

To all whom it may concern:

Be it known that I, SAMUEL R. VASBINDER, a citizen of the United States, residing at Fulton, in the county of Whiteside and State of Illinois, have invented a new, original, and ornamental Design for a Tire-Casing, of which the following is a specification, reference being had to the accompanying drawings, forming a part thereof.

The figure is a plan view of a design for tire casing showing my new design.

I claim:

The ornamental design for a tire casing, as shown.

SAMUEL ROSS VASBINDER.
